Attorney, Agent, or Firm—William F. Mufatti

[57] **CLAIM**

The ornamental design for a combined kaleidoscope and holder, as shown and described.

DESCRIPTION

FIG. 1 is a perspective view of a combined kaleidoscope and holder showing my new design the opposite side being a mirror image;

FIG. 2 is a perspective view of the holder shown separately for clarity of disclosure, the opposite side being a mirror image; and,

FIG. 3 is a bottom perspective view of the kaleidoscope shown separately for clarity of disclosure, the opposite side being a mirror image.

1 Claim, 2 Drawing Sheets

FIG. 1

FIG. 2

FIG. 3
